UNITED STATES PATENT OFFICE.

HENRY SCHUESSLER, OF AMITYVILLE, NEW YORK.

DESIGN FOR A MIRROR-FRAME.

SPECIFICATION forming part of Design No. 23,559, dated August 14, 1894.

Application filed July 18, 1894. Serial No. 517,947. Term of patent 3½ years.

To all whom it may concern:

Be it known that I, HENRY SCHUESSLER, a subject of the Emperor of Germany, residing at Amityville, in the county of Suffolk and State of New York, have invented a new Design for Mirror-Frames, of which the following is a specification.

The accompanying drawing represents a face-view of a mirror-frame, embodying my new design.

The leading feature of my design consists of a frame having arabesque ornaments, and in which a human-figure appears in seated position at one end, underneath of which scroll-like or volute figures are disposed, and at the other end of which appears a cherub, such scroll-like or volute figures being extended under such cherub, the lower edge of the frame having a foot at each end also ornamented by means of scroll-like or volute figures.

The frame A is shown as ornamented by a human figure *a* in seated position and represents an angel holding a lyre *a'*, behind which is arranged a scroll-like or volute figure *b*, and underneath of which are disposed scroll-like or volute figures *c* arranged in various

positions. The scroll-like or volute figures *c* extend along the front of the frame to and a short distance beyond a cherub *d*, which merges into the ornaments below it, both said figure *a* and the cherub *d*, forming the outline of the upper edge of the frame in connection with the upper scroll-like or volute figures. The feet *e*, *e'*, at each end of the frame are also ornamented by scroll-like or volute figures *f*. Mottled spaces *g* appear throughout the frame and are located between the scrolls and the branches or filaments thereof, a lattice or open-work portion *h* being arranged under the border *h'* which forms the seat for the figure *a*.

Having thus described my invention, I claim as new and desire to secure by Letters Patent—

The design for mirror-frames, substantially as shown and described,

In testimony that I claim the foregoing as my invention I have signed my name in presence of two subscribing witnesses.

HENRY SCHUESSLER.
